UNITED STATES PATENT OFFICE.

WALTER L. PIPES, OF ELIZABETH, NEW JERSEY, ASSIGNOR TO THE SHOE HARDWARE CO., OF WATERBURY, CONNECTICUT, A CORPORATION OF CONNECTICUT.

MULTIPLE-FASTENING DEVICE.

Application filed July 24, 1926. Serial No. 124,758.

This invention relates to separable fasteners, and particularly to that type of fastener for overshoes, garments, automobile curtains and other purposes where two flexible stringers are locked and unlocked by a slider, the locking being effected by travel in one direction and unlocking by an opposite movement.

The object of the invention is to provide an exceedingly simple locking device which will accordingly be very cheap to manufacture, which may be light in weight, small in size, and yet adapted to give a strong and durable union.

A feature of the invention lies in the simplicity of the device employed, the engageable members being only slightly curved or semi-cylindrical in form. Another feature of the invention lies in the slightly arched surface of the locking members whereby a bearing surface is provided which permits the members to meet in an edge and to be guided readily into an overlapping position.

According to the present invention the locking members are all alike and are therefore interchangeable. The locking members are adapted to be clamped upon the stringers which may be of any suitable type but preferably consists of a fabric tape having a beaded or corded edge upon which the locking members are clamped. The locking members consist of a slotted portion adapted to receive the corded edge of the fabric, and engageable portions which are slightly curved or arched, the members being adapted to engage or overlap in such a manner that the concave surface of one member fits over the convex surface of another when in locked relation. The members secured to one stringer alternate with those on the other so that when the sliding device is moved back and forth the locking members will be engaged and disengaged according to the direction of movement.

The invention resides particularly in the form of the engageable portions of the locking members, the smooth and slightly curved surface of which causes the contacting members to meet in an edge and move readily over one another into locking position. This invention discloses a fastener which is far more simple than those previously thought to be required. It may be substantially square or rectangular in shape and only very slightly curved to prevent its disengagement when in interlocked position. It has been found in practice that this simple type of fastener is

very practical, will resist either lateral or longitudinal tension, and is adapted to be very easily and evenly adjusted.

In the following drawings:

Figure 1 is a front elevation view partly in cross section on an enlarged scale of a fastener embodying this invention.

Fig. 2 is a cross section on line *a—a* of Fig. 1.

Fig. 3 is a transverse section of the locking members.

Fig. 4 is a longitudinal cross section of the locking members showing their staggered arrangement.

Fig. 5 is a detailed view of one of the locking members.

Referring to Fig. 1 it will be seen that the stringers 1—1 have at their abutting edges beads or cords 2 upon which the interlocking members are securely fastened. The stringers may be secured together at one end by a fastening link such as 3 and will have suitable stopping members such as 4 at the opposite end to limit the movement of the slider. A sliding cam operating device 5, many varieties of which are well known, is mounted upon both stringers. Preferably it will be Y-shaped, branches 6 being separately mounted on the stringers thus forming a tongue which upon movement in one direction serves to engage the locking members and upon movement in the other direction to disengage them. The slider may be operated by means of a ring 7 secured to it by the rivet 8.

Fig. 5 represents one of the locking members having a slotted portion which consists of the jaws 9 and a slightly curved or arched portion 10 which is substantially semi-cylindrical in form. As clearly shown in Figs. 4 and 5 of the drawing, the interengageable portion of the fastening element is preferably of the form of a segment of a hollow cylinder. The engageable portion 10 may be of any desired shape but is preferably a simple stamped form substantially rectangular in shape and slightly curved longitudinally. Heretofore it has been thought necessary to have a complex locking arrangement such as a recess in one member into which a projection on another member is adapted to be fitted. It has been found, however, that substantially flat and only slightly curved engageable members when secured to stringers in the proper relation will interlock and bind

together and give an exceedingly firm and durable union. The advantages of this type of fastener over the more complicated forms previously used is apparent since it is simple 5 to make, more inexpensive and being less likely to bind, may be locked and unlocked very smoothly and easily, forming at the same time an exceedingly firm and durable locking means.

- 10 In an accompanying application Serial No. 124,757 applicant has disclosed a type of fastener which has a curved surface but which is also circular or saucer shaped in form. This disclosure is primarily of an interlocking 15 member which is not circular in form but may be rectangular, square or any convenient shape and which may be almost flat in contour.

Having thus described my invention, what 20 I claim and desire to protect by Letters Patent is:

1. In a multiple type of fastener, a plurality of like members adapted to be interlocked and disengaged in and from nested 25 relation by a slider, said members having engageable portions, with unbroken concave and convex surfaces which are substantially straight in one direction.

2. In a multiple type of fastener, a plu-

rality of like members adapted to be interlocked and disengaged in and from nested relation by a slider, said members having engageable portions with unbroken concave and convex surfaces which are straight in a direction at right angles to the length of the members. 35

3. In a multiple type of fastener, a plurality of like members adapted to be interlocked and disengaged in and from nested relation by a slider, said members having engageable portions having the form of a segment of a hollow cylinder, the engageable portions being of uniform cross section. 40

4. In a multiple type of fastener, a plurality of like members adapted to be interlocked and disengaged in and from nested relation by a slider, said members having engageable portions having the form of a segment of a hollow cylinder, the engageable portions being of uniform cross section, and 45 each cylindrical surface of the engageable portion having a radius of curvature many times as great as the thickness of the member. 50

Signed at New York, county of New York, 55 State of New York, this 13th day of July, 1926.

WALTER L. PIPES.
